(57) **CLAIM**

The ornamental design for a power outlet camera, as shown and described.

DESCRIPTION

FIG. 1 is a top, first side, and front perspective view of a power outlet camera embodying the new design;

FIG. 2 is a bottom, first side, and front perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

The broken lines depict portions of the power outlet camera in which the design is embodied that form no part of the claimed design.
